UNITED STATES PATENT OFFICE.

LOUIS GODDU, OF WINCHESTER, MASSACHUSETTS, ASSIGNEE TO GODDU SEWING
MACHINE CO., OF PORTLAND, MAINE, A CORPORATION OF MAINE.

SOLE-SEWING MACHINE.

940,637.

Specification of Letters Patent. Patented Nov. 16, 1909.

Application filed August 31, 1900. Serial No. 28,624.

To all whom it may concern:

Be it known that I, LOUIS GODDU, a citizen of the United States, residing at Winchester, in the county of Middlesex and 5 State of Massachusetts, have invented certain new and useful Improvements in Sole-Sewing Machines; and I do hereby declare the following to be a full, clear, and exact description of the invention, such as will enable others skilled in the art to which it applies to make and use the same.

The present invention relates to sole sewing machines of the lock stitch type and has for its object to improve the construction 15 and arrangement of certain parts of such a machine whereby the parts are better adapted to coöperate with each other to perform their inter-related functions, and the machine as a whole is improved as to construction 20 and mode of operation.

More particularly my invention has for its object to improve the construction and arrangement of those parts of a shoe sewing machine which constitute the stitch forming 25 mechanism, and those devices which coöperate with the stitch forming mechanism in producing the seam.

With this object in view my invention consists in the devices and combinations of 30 devices hereinafter described and claimed.

In the accompanying drawings, I have shown my invention as applied to the machine disclosed in my United States Patent, No. 581,817, dated May 4, 1897, but it is to be understood that my invention is not limited to such application but may be applied to other shoe sewing machines without departing from the spirit thereof.

Referring to the drawings, Figure 1 is a 40 sectional view of the machine described in the patent above referred to modified according to my present invention, the view corresponding to Fig. 3 of the said patent, Fig. 1^a is a detail view of a locking device to be referred to, Fig. 2 is a sectional view on the same plate as Fig. 1, but looking in the opposite direction, Fig. 3 shows the awl segment, the awl, and the rock-shaft to which it is fixed, detached; Fig. 4 shows the needle segment, the needle, and needle-guide, detached, Fig. 5 shows the stop for the needle guide; Figs. 6, 7, 8 and 9 show details of the shuttle, the work-support, and some other parts together with stock lying on the work-support, said figures illustrating the forma-

tion of the stitch; Fig. 10 is a top view of the work support, with part of the looper to represent its path when feeding the needle with thread; Fig. 11 is a view in front elevation of the thread winding mechanism, 60 and, Fig. 12 is a sectional view showing details of such mechanism.

The frame of the machine, the driving shaft journaled therein, the arrangement of cams on the driving shaft, the mechanism 65 for rotating the shuttle, the awl and needle devices with their actuating mechanisms and the mechanism for actuating the take-up arm are the same as in the machine disclosed in Patent #581,817 above referred to, and a 70 detail description thereof is therefore deemed unnecessary in this application.

The shuttle case *h*^x is substantially the same as in the patent referred to, and is supported and actuated in substantially the 75 same manner. In my present invention, however, the shuttle case is arranged to receive a bobbin spool, and the thread is led from the bobbin, and guided and controlled in its passage to the work by certain novel 80 devices which will now be described. The face plate or cap of the shuttle is provided with the hollow stud *k*⁴ adapted to be slipped over a stud *k*⁴ extending from the end *h* of the shuttle and to form a bearing 85 for the bobbin spool *k*. The face plate has a block 26 rigidly secured thereto so as to form a part thereof, provided with a boss having formed therein a recess, see Fig. 7, to receive the free end of the stud *k*⁴. A 90 spring *k*⁶ secured to the face plate by the screw *k*⁸ passes through an opening in the side of the block 26 and engages a groove *k*⁵ in the end of the stud *k*⁴ to hold the face plate in place. At the top of the face plate 95 and projecting backwardly into the shuttle case is an arm *h*⁶ provided with a thread case is an arm *h*⁶ provided with a thread opening and a groove leading from the thread opening to a groove in the front face of the 100 face plate. Directly below this groove and at the upper end of the block 26 is a projection 28 having a thread groove in its side, and arranged to press against the thread in said groove is a tension spring *k*¹⁰ secured 105 to the face plate by the screw *k*⁸. The free end of the spring *k*¹⁰ bears against a shoulder formed by a projection from the face plate above the thread rest 28 and the spring 110 can be adjusted to bear with more or less

pressure on the thread by means of the screw k^8 . At the lower end of the block 26 a thread opening 27 is formed and at a short distance below the opening 27 the face plate 5 is provided with a forwardly extending projection, the projection being extended downwardly to form a nose similar to that shown in Patent No. 581,817, and having a thread guiding groove.

10 As will be clear from Figs. 6 and 7, the shuttle-thread passes from the bobbin through the opening in the arm h^6 along the grooves in the arm h^6 and upper portion of the face plate under the tension spring k^{10} through the opening 27 across the space h^9 between the block 26 and the projection on the face plate, along the groove in the nose to the work.

Herein provision is made as in the patent 20 referred to for measuring off from the bobbin in the shuttle a sufficient portion of thread for the next stitch, but herein the devices instrumental in measuring off the thread differ materially from those described 25 in said patent. Herein the measuring device is shown as a finger 10 scooped out at its inner side at 12, to form an edge or lip as represented in section, Fig. 7, the extremity 13 of the measuring device being 30 located in such position that when the finger 10 is moved, it will enter the notch h^9 and act on the shuttle-thread, while the latter is stretched between the nose and stock, and will measure off from the bobbin the thread 35 required for the next stitch, leaving said thread with slack to be taken up as the shuttle next passes through the loop of needle-thread. The upper end of this finger 10 is clamped by a clamp screw 14 in the split 40 end 15 of a rocker 16 fitted to surround and turn on the end 17 of a lever 18 pivoted at 19 on the head of the machine.

The upper arm of the rocker 16 receives in it a headed bolt 17*, the shank of which is 45 surrounded by a spring 18, a threaded hollow nut 19* being screwed into the rocker to compress said spring and force said bolt against a flattened post of the end 17 of the lever, see Fig. 1, said spring-pressed bolt 50 constituting a retaining device to maintain the rocker and its measuring finger in correct working position, yet whenever the operator desires to turn the measuring finger away from the cap of the shuttle, to replace the shuttle-thread, or for any other purpose, he may by striking the rocker, turn it on the projection 17, the head of the bolt at such time slipping off from the said flattened face. The rear end of this lever 18 is 55 provided with an anti-friction roll 21 held thereon loosely by a screw 30, see Fig. 1, the edge of said roll running against the edge of a cam 31, herein shown as connected with or forming part of the toothed gear h^{23} . 60 The lever 18 is acted upon by a spring 32,

which keeps the roller 21 against the cam 31, this cam actuating the measuring device once during each stitch.

The needle thread t is taken from a wax-pot P , through a stripper P' , and is then led once about a sheave o , mounted on a stud o' , and from thence the needle thread is carried about the inner side of a tension sheave o^2 , and thence over the outer side of a second tension sheave o^3 , the studs carrying said sheaves being all mounted on the take-up lever m . The tension disks o^2 and o^3 constituting tension devices, are located close to the center of motion D of the take-up lever, so that their weight does not affect 75 the momentum of the take-up. The tension exerted on the thread extended over said sheaves o^2 and o^3 , may be varied at will by means of a nut n , on a stud n' extended from said take-up lever, and arranged to press 80 against a spring n^2 which bears upon the central parts of the said tension devices, so that by turning said nut the tension may be regulated as desired.

The needle-thread is taken from the tension wheel or disk o^3 over a loose sheave n^3 of very light weight, mounted on a stud n^4 at the end of the take-up lever, the said sheave being retained on the said stud by a wire lip n^5 , and thence the thread t is extended over a sheave n^6 on a stud n^7 fixed to the frame-work, or to a steam heated chamber n^{70} forming part of the frame-work, and thence the thread is shown as led through a groove n^8 at the underside of the 100 work-support f , said thread passing from said groove through an opening n^9 and meeting the stock through the hole f^3 in the top of the work support.

The take-up arm herein described, being 105 made of thin metal, is very light in weight, and by mounting the tension devices close to the center of motion of the actuating shaft D , the strains due to momentum, which said take-up has to overcome in rapid movement, are reduced to a minimum, and further said arm is made to reciprocate against a heated box n^{70} , so that said arm, the sheave n^3 , and tension devices are kept properly heated so that the wax will not stick. In the 110 vibration of this arm, the sheave or roller o' acts at each movement of the sheave n^3 toward the work support, to draw from the wax pot a sufficient length of thread to be used in making a stitch in stock of maximum thickness.

In operation the take-up is actuated in the same time, and order with relation to the rotating shuttle to take-up the loop of needle thread, as provided for in said patent, but herein the tension devices o^2 and o^3 take the place of two rolls carried by the take-up in said patent, and the extremity of the arm has but a very light sheave.

The location of the heavier tension de-

vice near the center of motion D of the take-up arm, and the addition to the take-up arm of the sheave o' to pull off the thread, adds very materially to the effectiveness of 5 the machine, for the reason that the momentum generated in the take-up arm which has to be overcome at each stroke, is very materially lessened, and the speed of the machine may be increased without fear of 10 breaking the take-up lever.

The mechanism of Patent No. 581,817 for locking and releasing the presser-foot has been slightly modified as shown in Fig. 1 by omitting the ratchet plate and pawl for 15 positively raising the presser foot during the feeding movement of the awl. Otherwise the construction and operation are substantially the same as in the machine of the patent.

20 The shank of the work support f has a groove n⁸ for the thread t, and at the upper end of said groove a passage n⁹, the lower side of which is inclined as best represented in Figs. 6 and 9, the said inclined side presenting a hard finish smooth edge by inserting in it a steel wearing face n¹⁸ composed as shown of a round piece of steel wire n¹⁹ hardened, such face notwithstanding the wear of the thread and obviating the 30 otherwise frequent renewal of work supports. The wearing face is inclined and receives upon it the thread t, and the latter under the strain put upon it in the process of making stitches has a tendency to ride 35 down the incline, and especially so when the work is fed over the work-support by the awl as represented in the detail Fig. 9.

The groove n⁸ in the shank of the work-support is entered by a closure e, shown as a 40 lever pivoted at e', the upper end of said lever being extended above said passage, and shielding the waxed thread, so that the wax cannot possibly get on the face of the work-support and contact with the upper of the 45 shoe being stitched. The lower end e' of this closure e may be struck by the operator whenever it is desired to get access to the thread in the passage n⁸ or to seize the thread and draw it through the passage n⁹ 50 in threading up the machine. The closure e has coöperating with it a suitable locking device e², it being shown as a screw having the underside of its head rounded to enter a slot in the closure, the edges of said slot being beveled, see detail Fig. 1^a. The screw is surrounded by a spiral spring, and the nut on the end of the screw acting on the end of the spring regulates the force of the spring in pulling the underside of the head of the 55 screw into the slot, so that the said closure is held frictionally either closed or opened.

The looper d is substantially straight, and it has near its end a hook d', and the looper is carried by a lever d² so mounted as to have 60 a substantially universal motion. The lower

end of the lever d² has a hollow hub d³ which is slipped over a stud d⁴ extended from a hollow sleeve d⁵, mounted on a stud d⁶ fixed to the head. The sleeve d⁵ is retained on said stud by a set screw d^{6x}, while the sleeve 70 d³ is retained on the stud d⁴ by a similar screw. The lever d² has a backwardly extended stud d¹², which engages a cam surface formed on the side of the disk H, the said cam surface being of a shape to turn the 75 lever d² about the stud d⁴ as a fulcrum. The lever d² has a roller or other stud d⁷, which is borne against the cam shaped periphery of the disk H, by a spring d⁹ acting on a stud d¹⁰ extended from the said lever, the 80 periphery of said disk H imparting to the lever a movement about the stud d⁴. The spring d⁹ also acts to hold the stud d¹² against the cam surface on the face of the 85 disk H.

In operation the looper d starts forward, so that its hook passes the needle thread at its outer side, said needle thread being extended from the passage n⁸ to the opening f² in the throat of the work-support, and between said thread and the work support, and the hook of the looper engages the said thread and carries it up the inclined part of the passage n⁸ into substantially the position shown in Fig. 9, and thereafter the needle b⁹ 90 descends at the inner side of the thread held by the hook, and as the needle is moving in its lowest position, the looper is moved toward the main shaft of the machine and also retracted, taking with it the needle-thread 95 and forming it in a loop, so that both bights of the loop are stretched across the shank of the needle, as in Fig. 10, and the needle in rising engages the loop held against it, and the thread having been caught by the hook 100 of the needle, the looper is immediately moved forward to release the loop of needle-thread drawn out by it, giving up the loop so held by it to the needle as the latter rises through the stock. The looper by its movements and action furnishes sufficient length 105 of needle thread to the needle to enable the latter to rise and draw the loop through the stock without the rendering of the thread 110 through the hook of the needle, thus fraying 115 it.

Heretofore it has been customary to wind the thread to be used in the shuttle on separate thread-winding machines, but herein I have provided means connected with the sewing machine and wax pot for winding the waxed thread onto the spool so that it may be readily applied to the bobbin when exhausted, the thread being wound during the regular operations of the machine.

The right-hand end of the main shaft A² of the machine will have secured to it a fast pulley or hand-wheel and a loose pulley B³, all as in said Patent No. 581,817. Herein the loose pulley is chambered at its inner 120 125 130

side to receive a pulley A¹⁰ secured to a short shaft A¹² mounted in a bearing at one end of a lever A¹³, said lever having a sleeve-like hub A^{10x} which is extended through a bearing A^{12x} projected from an upright A³³ mounted on the plate A³⁴ forming part of the head of the machine. The sleeve A^{10x} receives upon its opposite end a lever A¹⁴ having a cam surface r against which operates 5 the end r' of a lever r² pivoted at r³. The shaft A¹² has fast upon it a belt wheel A¹⁵ which receives a belt A¹⁶, which is extended over a belt-wheel A¹⁷, fast on a shaft A^{15x} within the sleeve A^{10x}. The end of the shaft 10 A^{15x} outside of the belt wheel is provided with a screw threaded portion on which is screwed the disk A¹⁸ and a slightly reduced portion forming a bearing for the spool k. The spool is held on the shaft by means of 15 the flanged block A¹⁹, the screw threaded stud A²⁰ of which engages a threaded hole in the end of the shaft. By turning the disk A¹⁸ the spool is clamped with any desired friction between the disk and the flanged block A¹⁹. The disk A¹⁸ also serves as a 20 convenient means for forcing the spool endwise off the shaft when the flanged block A¹⁹ has been removed.

The lever A¹³ has pivoted upon it at u, a lever u' forming part of a thread cutting mechanism, said lever having attached to it a notched block u², which receives in it the short arm u³ of a let-off lever u⁴ pivoted at u⁵, and the lever u' is acted upon by a 30 suitable spring u⁶ to actuate the lever u' and throw it toward the cutter or blade u⁷ fast on a projection u⁸ of the said lever A¹³.

Whenever the thread mass wound upon the projecting end of the rod A^{15x} is of the 40 proper size to substantially fill the bobbin, then the outer coils of the thread will meet the flattened end of the lever u⁴ and will turn it so that its end u³ retires from the notch u², letting the spring u⁶ immediately 45 actuate the lever u', causing the latter to descend upon the thread passing between it and the blade u⁷, and cut the same off.

The waxed thread to be wound on the spool to be applied to the shuttle, is taken 50 from one end of the wax-pot P, and is led over suitable tension wheels, and through the space between the open cutting mechanism described, to the winding spindle or rod A^{15x}.

55 The belt A¹⁶ and the winding spindle may be left at rest until when it is desired to wind a spool for the bobbin, and at such time the operator will turn the lever r² in the direction of the arrow near it in Fig. 1, causing 60 the short arm r' to act upon the incline r and turn the sleeve A^{10x} and its lever A¹³ in a direction to force the pulley A¹⁰ against the interior of the loose pulley B³.

Providing the sewing machine itself with 65 the winding mechanism enables the operator

to save much of his time heretofore employed in winding thread for the shuttles.

Having described my invention, what I claim and desire to secure by Letters Patent is:-

1. A lock-stitch shoe-sewing machine having, in combination, a needle, a shuttle, means for actuating the needle and the shuttle to interlock the needle and shuttle threads, a depending nose on the face of the shuttle provided with a forwardly-open thread guiding groove, and a tension device in the face of the shuttle located above and substantially in line with said groove, the tension device comprising members engaging the thread laterally but not in front, so that by drawing the thread downwardly it may be at once drawn into position in the tension device and the shuttle nose, substantially as described. 70

2. A lock stitch shoe sewing machine, having, in combination, a needle, a shuttle, means for actuating the needle and shuttle to interlock the needle and shuttle threads, a cap to close the open face of the shuttle to inclose the shuttle thread, said cap having an extended grooved nose and being provided with a thread rest above said nose projecting at one side of the shuttle thread, said thread rest being independent of the nose and at a distance therefrom and a tension spring to act on the shuttle thread lying on the side of the said rest, substantially as described. 80

3. A lock stitch shoe sewing machine, having, in combination, a needle, a shuttle, means for actuating the needle and shuttle to interlock the needle and shuttle threads, a cap to close the open face of the shuttle to inclose the said thread, said cap being provided with a projecting thread rest, a tension spring to act on the shuttle thread lying on said rest, and a projection from said cap for supporting the free end of said spring, substantially as described. 100

4. A lock stitch shoe sewing machine, having, in combination, a needle, a shuttle, means for actuating the needle and shuttle to interlock the needle and shuttle threads, a cap to close the open face of the shuttle to inclose the said thread, said cap having an extended split nose, an open thread guide above and independent of said nose in which the thread may be drawn, and a thread rest independent of said thread guide and nose to sustain the shuttle thread, and a spring to act on the thread lying on said rest, to determine its tension, substantially as described. 115

5. A lock stitch shoe sewing machine, having, in combination, a needle, a shuttle, means for actuating the needle and shuttle to interlock the needle and shuttle threads, said shuttle being provided with a notch at its face, a measuring device composed of a finger to act on the shuttle thread opposite 125

- 5 said notch, a lever, a laterally movable support for said finger carried by said lever, and means for actuating the lever, substantially as described.
- 10 6. A lock stitch shoe sewing machine, having, in combination, a needle, a shuttle, means for actuating the needle and shuttle to interlock the needle and shuttle threads, a measuring device comprising a finger to act on the shuttle thread and extending in front of the shuttle, mechanism for actuating the finger, and connections between the finger and its actuating mechanism whereby the finger may be moved from in front of the 15 shuttle, substantially as described.
7. A lock stitch shoe sewing machine, having, in combination, a needle, a shuttle, means for actuating the needle and shuttle to interlock the needle and shuttle threads, 20 said shuttle having at its front side a notch, a measuring device composed of a finger having an edge or lip to act on the shuttle thread opposite said notch, a rocker carrying said finger, a lever on which said rocker is mounted, means to hold said rocker and 25 measuring device in operative position, and means to move said lever to cause the said measuring device to depress the thread into said notch, substantially as described.
- 30 8. A lock-stitch shoe-sewing machine having, in combination, a needle, a shuttle, means for actuating the needle and shuttle to interlock the needle and shuttle threads including a shuttle driver and an actuating 35 shuttle shaft, a cap to inclose thread in said shuttle, said cap having a depression which is crossed by the shuttle thread, a measuring device having an edge or lip to act on the shuttle thread, a lever carrying said measuring 40 device fulcrumed outside the periphery of the shuttle and a cam moved in unison with said shaft to operate said measuring device once for each stitch, substantially as described.
- 45 9. A shoe sewing machine, having, in combination, a needle, a looper, means for actuating the needle and looper, a work support having a groove to receive the thread on its way to the needle and a closure for said 50 groove to prevent the wax on the thread getting on the outside of the work support, and then on the upper of the shoe being stitched, substantially as described.
- 55 10. A shoe sewing machine, having, in combination, a needle, a looper, means for actuating the needle and looper, a work support having a groove to receive the needle thread on its way to the needle, a closure for said groove to prevent the wax on the thread
- getting on the outside of the work support 60 and then on the upper of the shoe being stitched, and means to hold said closure shut or open, substantially as described.
11. A lock stitch shoe sewing machine, having, in combination, a needle, a shuttle, means for actuating the needle and shuttle to interlock the needle and shuttle threads, a cap to close the open side of said shuttle, a hollow stud projecting from said cap to form a bearing for the bobbin, a stud on the 65 shuttle arranged to enter said hollow stud, said cap having a recess at its inner side extending part way only through the cap to receive the outer end of the shuttle stud, and a locking device mounted on the cap arranged to engage the shuttle stud, substantially as described.
12. A lock stitch shoe sewing machine, having, in combination, a needle, a shuttle, means for actuating the needle and shuttle to interlock the needle and shuttle threads, 70 said shuttle having a stud notched near its outer end, a cap to close the open side of said shuttle said cap having at its face a boss recessed at its rear side to fit over said stud, said boss being slotted at its side next the face of the cap, and a locking device carried by said cap and extended through the slot in the boss to engage said stud, substantially as described.
13. A lock stitch shoe sewing machine, having, in combination, a needle, a shuttle, means for actuating the needle and shuttle to interlock the needle and shuttle threads, 75 said shuttle having a stud notched near its outer end, a cap to close the open side of said shuttle and a locking spring mounted on said cap and arranged to engage the notched end of said stud, substantially as described.
14. A lock stitch shoe sewing machine, having, in combination, a needle, a shuttle, means for actuating the needle and shuttle to interlock the needle and shuttle threads, 80 a stud projecting from the shuttle and provided with a notch near its outer end, a cap to close the open side of said shuttle provided with a slot, and a locking device carried by said cap and extending through the slot to engage the notch in said stud, substantially as described.
- 100 In testimony whereof I affix my signature, in presence of two witnesses.
- LOUIS GODDU.
- Witnesses:
- HORACE VAN EVEREN,
ALFRED H. HILDRETH.

It is hereby certified that in Letters Patent No. 940,637, granted November 16, 1909, upon the application of Louis Goddu, of Winchester, Massachusetts, for an improvement in "Sole-Sewing Machines," errors appear in the printed specification requiring correction as follows: Page 1, line 77, the word "chuttle" should read *shuttle*, and same page, the line 97 should be canceled; and that said Letters Patent should be read with these corrections therein that the same may conform to the record of the case in the Patent Office.

Signed and sealed this 21st day of December, A. D., 1909.

[SEAL.]

C. C. BILLINGS,

Acting Commissioner of Patents
